UNITED STATES PATENT OFFICE.

RAY SETH WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 14, 1920. Serial No. 430,652.

To all whom it may concern:

Be it known that I, RAY S. WILBUR, a citizen of the United States of America, residing at Lyndhurst, in the county of Bergen, State of New Jersey, have invented certain new and useful Improvements in Telephone-Exchange Systems, of which the following is a full, clear, concise, and exact description.

10 This invention relates to telephone exchange systems and more particularly to such systems in which toll connections are established between exchanges by means of machine switching equipment controlled over toll lines.

15 Objects of the invention are to provide improved methods and means for enabling an operator at one exchange to extend a connection over a toll line to a subscriber's station at a distant exchange by means of automatic switching mechanism and to provide the operator with complete supervision over such a connection.

20 Another object of the invention is to provide suitable circuit arrangements in a system of this nature so that traffic may be handled in either direction over the same circuit.

25 Further objects are to improve the supervision over long lines and to translate combinations of equal numbers of current impulses into combinations of varying numbers of current impulses.

30 To attain the objects of the invention means are provided whereby, the building up of a connection from the originating exchange to the subscriber's station at the distant exchange, the application of ringing current to the called line, various supervisory signals at the originating exchange and the release of the connection are controlled by means of a plurality of relatively high frequency currents transmitted over the toll line.

35 More specifically the invention contemplates the provision of impulse transmitting means, whereby for each digit of a number desired, a plurality of impulses of relatively high frequency currents are transmitted over the toll line to an impulse receiving device, which filters, rectifies and translates these impulses into direct current impulses corresponding to a digit key depressed at the operator's position. A plurality of sources

of current of different frequencies at the 55 originating office are provided and various combinations of these frequencies are utilized for sending the various digits of the decimal system of notation.

60 The various supervisory signals and a flashing signal at the originating office are caused to be actuated by the simultaneous application of a plurality of different frequencies to the line, there being different combinations of frequencies for the different 65 signals transmitted.

These and other objects of the invention will be more readily understood by reference to the accompanying drawings, which when arranged as shown in Fig. 9 of the 70 drawings illustrate one embodiment of the invention. Fig. 1 shows a cord circuit at an originating toll operator's position a calling subscriber's line which may be associated with the toll operator's position in 75 any well-known manner, and the calling jack of one of the toll trunks appearing before the toll operator's position; Fig. 2 shows apparatus individual to the outgoing end of a toll trunk line, a receiving circuit 80 R and a switching device D, herein termed a distributor, for associating the receiving circuit R with the toll line; Fig. 3 shows apparatus individual to the incoming end of the toll trunk line, a receiving circuit R¹, 85 a switching device D¹, herein termed a distributor, for associating the receiving circuit R¹ with the toll line, and a line finder switch LFS for extending the toll line;

90 Fig. 4 includes a link circuit for extending the toll line, and a switching device RSF for associating the receiving and translating circuit R² with the trunk line; Fig. 5 shows a receiving and translating circuit R² for receiving relatively high frequency currents and translating them into direct 95 current impulses for the purpose of operating counting relays shown in Fig. 6 of the drawings; Fig. 6 shows a set of counting relays, a set of counting switches CT¹, 100 CT² and CT³, a set of pulsing relays, and a distributor D⁴; Fig. 7 shows a selector circuit; and Fig. 8 shows a connector circuit and the substation LL of a called subscriber's line terminating therein.

105 In general the system functions in the following manner: A subscriber at station HH, desiring a connection with a subscriber

LL at a distant exchange, first obtains a connection through the position of the usual A or answering operator to a toll switching trunk, whereby the connection is extended 5 to the toll operator's position. The toll operator answers with an idle cord AA and after ascertaining the number desired at the distant exchange, extends the connection by means of her calling plug over an idle toll line 10 extending to the desired distant exchange.

In response to the seizure of the toll line the cord selector switch CS, associated with the cord circuit, will operate to associate an idle impulse sender S with the cord circuit 15 AA, and a relay, associated with the trunk circuit, will operate to impress 900 cycle current on the outgoing end of the toll line so that when the distributor D¹, associated with the distant end of the toll line, 20 engages the contacts of the seized line, the 900 cycle current will actuate relays in the receiving circuit R¹, causing the operation of the toll line relay of the seized toll line at the distant office.

25 The line relay in operating causes the switch LFS to be operated, which in turn causes the operation of the finder switch RSF, thereby extending the toll line to the receiving circuit R².

30 As soon as the line finder switch LFS operates to extend the toll line, 1300 cycle current at the distant exchange is impressed upon the toll line conductors, which, in conjunction with the 900 cycle current at the 35 originating exchange, operates relays in the receiving circuit R, which operate the sender switch SW. The 900 and 1300 cycle currents are thereupon disconnected from the toll line and as soon as the number desired 40 by the calling subscriber has been set up by the operator on the sender S, a plurality of impulses of high frequency current will be transmitted over the toll line to the receiving circuit R² for each digit of the desired number. The receiving circuit R² is common to a plurality of toll lines and serves to translate and repeat impulses delivered thereto.

45 The sets of impulses transmitted by the distributor D³, corresponding to the depressed keys of the sender S, are filtered and rectified at the receiving circuit R², causing the switches FS¹, FS² and FS³ to be operated. Each time a set of impulses is transmitted from the sender to the receiving circuit R², certain relays associated with one or more of the switches FS¹, FS² and FS³ are operated to cause the operation of a particular counting relay, said counting 55 relay corresponding to the digit represented by the depressed key of the sender S.

60 The counting switches CT¹, CT² and CT³ are then successively operated, causing in turn the successive operation of as many of the pulsing relays associated with the dis-

tributor D⁴ as keys have been depressed at the sender S. The distributor D⁴, in rotating, will transmit impulses over impulse conductor 699 to the impulse relay 700 associated with the selector SL. In response 70 to the actuation of the impulse relay, selector switch SL and connector switch CC will be set upon the terminals of the desired line. As soon as the last impulse is delivered by the distributor D⁴, the switch RSF is operated, thereby freeing the receiving circuit R² and restoring all apparatus in said receiving circuit to normal position. 75

If the desired line is idle, 900 and 1100 cycle current will be automatically impressed 80 upon the toll line and will be received by the receiving circuit R, operating relays therein which will cause the supervisory lamp in the cord circuit to light, indicating that the ringing signal may be transmitted. 85

In transmitting a ringing signal, the operator depresses the ringing key, thereby simultaneously applying 900 and 1100 cycle current to the line conductors, which currents are received by the receiving circuit R¹. 90 Relays of the receiving circuit R¹ thereupon operate and cause ringing current to be impressed upon the line of the called subscriber for a period determined by the time required for the distributor associated therewith to 95 operate through two cycles. If it is desired that ringing current be continued, it is necessary for the operator to maintain the key actuated for the desired period.

When the called party answers, 900 and 100 1300 cycle currents will be connected simultaneously to the toll line for a period representing the time required for two cycles of the distributor. These currents are received by the receiving circuit R, causing the operation 105 of relays therein, which in turn cause the extinguishment of the supervisory lamp.

When the called subscriber restores the receiver to the switch hook, 900 and 1100 cycle currents are simultaneously connected 110 to the toll line for a period representing the time of two cycles of the distributor D. These currents are received in the receiving circuit R and cause the operation of relays 115 therein, which in turn cause the supervisory lamp to be lighted, indicating to the operator that conversation has ceased.

If the called subscriber flashes, 1100 and 1300 cycle currents will be connected simultaneously to the toll line, causing the connection of an interrupter to the sleeve circuit of the cord circuit AA, which will cause the supervisory lamp of the operator's cord circuit to be flashed. The operator noting the flashing signal may actuate her listening key whereupon the flashing signal will be disconnected. If the called line is busy, a busy signal will be transmitted to the operator. 120

125 As the toll line is adapted for use as a 130

two-way trunk, the equipment at the two ends of the toll line is identical. To simplify the drawings the necessary apparatus for establishing a connection from the originating exchange to the distant exchange only, has been shown complete. The cord selector switch CS, sender switch SW and sender S at the toll operator's position at the second exchange may be similar to corresponding apparatus shown in Fig. 1 of the drawings, and the apparatus for completing a connection originated at the operator's position at the distant exchange has been represented in Fig. 2 by a blank rectangle WA, it being understood that the apparatus contained within the rectangle is identical with that fully disclosed in Figs. 4 to 8 inclusive, and within the dotted lines in Fig. 3 of the drawings.

Devices for filtering and converting filtered currents into unidirectional currents are well known in the art and such devices have therefore been indicated simply by rectangles. These devices may be of the general type disclosed in Patent No. 1,261,290 of April 2, 1918 to P. M. Rainey. The apparatus herein termed distributors may be of any suitable design in which the contacts thereof are suitably insulated and are wiped over by constantly rotating brushes.

The operation of the system will be better understood from a detailed description thereof. Since the line of a calling subscriber such as HH may be extended to the operator at the originating exchange in a manner well known in the art, the description of such an extension will be omitted. It will be assumed that the operator at the originating exchange has answered a call from the calling station HH and has ascertained that a subscriber LL at the distant exchange is desired. The operator will therefore insert the calling plug 110 of the cord circuit AA into the jack 111 of an idle toll trunk line extending to the distant exchange. Insertion of plug 110 into the jack 111 causes the operation of relays 101 and 202 over a path extending from ground, winding of relay 202, sleeves of jack 111 and plug 110, and windings of relays 101 and 103 to grounded battery. Although current also passes through relay 103 at this time, said relay 103 does not operate since it is of the marginal type. Relay 101 in operating completes a circuit for relays 104 and 105 over a path extending from ground, armature and front contact of relay 101 and thence in parallel, one path extending through the winding of relay 104 to grounded battery and the other path extending through the left-hand armature and back contact of relay 107 and the winding of relay 105 to grounded battery. Relay 105 thereupon operates, thereby disconnecting the answering end of the cord circuit AA

from the calling end and connecting contacts of the cord finder switch CS to the calling plug 110 of the cord circuit. Relay 104 in operating completes a circuit for the operation of relay 106 over a path extending from ground, right-hand armature and back contact of relay 107, armature and front contact of relay 104, normal contact 199 and brush 125 of cord finder switch CS, winding of relay 106 and back contact and inner left-hand armature of relay 108 to grounded battery.

As soon as relay 106 operates, a circuit is completed for the stepping magnet 126 of the switch CS over a path extending from grounded battery, winding, armature and back contact of magnet 126, right hand armature and front contact of relay 106, brush 125 and contact 199 of switch CS, front contact and armature of relay 104, and back contact and right hand armature of relay 107 to ground. Magnet 126 thereupon operates and continues to operate to move the brushes 120 to 125 inclusive of the switch CS over its associated contacts as long as brush 125 engages busy contacts or contacts having ground potential thereon. As soon as brush 125 reaches a contact of a calling circuit or a contact having no potential thereon, relay 106 releases to open the stepping circuit. Relay 106 is preferably slow to release so as to maintain the circuit of magnet 126 closed during the stepping operation. In the present instance, it is assumed that the cord circuit AA is connected to the switch CS so that the relay 108 operates over a path extending from grounded battery, winding and right hand normal contacts of relay 108, left hand normal contacts of relay 106, brush 124 and contact 134 of switch CS, and back contact and right hand armature of relay 107 to ground. Relay 108, in operating, locks up through its right hand normal contacts and through brush 124 and contact 134 of switch CS to ground at the back contact and right hand armature of relay 107. Relay 108, in attracting its inner left hand armature, removes battery from the winding of relay 106, and in attracting its intermediate left hand armature, connects ground to contact 135 of the switch CS for the purpose of rendering the selected set of contacts busy. At the outer left hand armature and front contact of relay 108, the conductor 128 is extended to the brush 141 of the sender switch SW.

When the brush 120 of the switch CS moves into its second position, an obvious circuit is closed for the lighting of lamp signal 136 which serves not only as a guard signal but to indicate the particular sender which has been selected if a plurality of cord selectors have been employed. It will be obvious that conductors such as 127 130

and 128 leading to the cord AA may be multiplied to the contacts of one or more other switches similar to CS with each of which a sender may be associated.

- 6 When relay 202 of the toll trunk line circuit operates, a circuit for relays 209 and 210 is completed over a path extending from ground, armature and front contact of relay 202 and thence in parallel, one path extending through the left hand armature and back contact of relay 216 and the winding of relay 209 to grounded battery, and the other path extending through the winding of relay 210 to grounded battery. Relay 10 209, in attracting its left hand armatures, renders the outgoing end of the toll line circuit discontinuous and connects 900 cycle current to the line circuit. When the distributor D¹, shown in Fig. 3 of the drawings, 15 engages contacts of this line, the 900 cycle current flows into the receiving circuit R¹.

The 900 cycle current flows into the receiving circuit R associated with the distributor D but it will not produce any effect on the line relay at the originating exchange due to the circuit for said line relay being open at the contacts of relay 250, the operation of which will be later described. Relay 210 in operating completes a circuit for relays 225, 241 and 250 over a path extending from ground, inner right hand armature and front contact of relay 210, thence in parallel, one path extending 25 through the left hand normal contacts and winding of relay 225 to grounded battery, and the other path extending through the windings of relays 241 and 250 in series to grounded battery. Relay 225, in operating, locks up through its left hand alternate contacts to ground at the outer left hand armature and back contact of relay 240. Relay 225 in operating also prepares a circuit for the application of 1100 and 1300 cycle current to the line conductors, the function 30 of which is to cause the release of the connection as will be later described. Relay 241, in operating, connects the relays 214, 240, and 224 in operative relationship with the distributor D and opens the conductors 35 of the line circuit extending to a line finder (not shown) associated with the outgoing end of the toll line similar to LFS, shown in Fig. 3 of the drawings. Relay 250, in operating, connects the relays 201 and 220 in operative relationship with the distributor D.

When the 900 cycle current is connected 40 to the line circuit, relay 301 of the receiving circuit R¹ operates by induced current from the source 230, over a path extending from grounded battery, armature and back contact of relay 307, winding of relay 301 through the 900 cycle frequently filter 300f, brush 341 and contact 361 of the distributor

D¹, right hand winding of repeating coil 380, contact 360 and brush 340 of the distributor D¹ and through the 900 cycle filter 300f, to ground. Relay 301, in operating, 70 closes a circuit for the operation of line relay 310, over a path extending from grounded battery, through the winding and the left hand normal contacts of line relay 310, right hand normal contacts of cutoff relay 311, back contact and outer right hand armature of relay 315, contact 366 and brush 346 of the distributor D¹, back contact and left hand armature of relay 303, left hand armature and back contact of relay 302, and left hand armature and front contact of relay 301 to ground. Relay 310, in operating, 75 locks through its left hand alternate contacts and through the back contact and left hand armature of cutoff relay 311 to ground. Relay 310, in operating, also places 80 ground, through its inner right hand alternate contacts on contacts 375 and 377 of switch LFS for the purpose of starting the operation of the line finder switch LFS. Although only one line finder switch has 85 been shown it is to be understood that the use of a plurality of line finder switches such as LFS is contemplated. By the use of well known arrangements only one line 90 finder can be made to seize and rest on the terminals of the calling line so that the operation of only one switch is described herein.

As soon as ground is placed on the contact 377 of switch LFS, relay 404 operates 100 over a path extending from grounded battery, left hand armature and back contact of relay 405, winding of relay 404, brush 336 and contact 377 of switch LFS and front contact and inner right hand armature of relay 310 to ground. Relay 404, in operating, 105 completes a circuit for stepping magnet 390 for the switch LFS over a path extending from grounded battery, winding and armature and back contact of magnet 390, left hand armature and front contact of relay 404, brush 335 and contact 375 of switch LFS, and front contact and inner right hand armature of relay 310 to ground.

Under the control of motor magnet 390, 110 the brushes of the switch LFS step to the line taken for use, whereupon relay 404 releases due to the opening of its circuit at the back contact and outer right hand armature of line relay 310, thereby opening the operating circuit for magnet 390, and relay 405 then operates in series with the cut-off relay 311 over a path extending from grounded battery, armature and back contact of relay 312, winding of relay 311, contact 374 and brush 334 of switch LFS, right hand armature and back contact of relay 404, right and normal contacts and winding of relay 405 to grounded battery. 120 125 130

- Relay 405 then locks through its right hand alternate contacts in series with cut-off relay 311 over the circuit just traced. Relay 311, in attracting its left hand armature, opens the locking circuit for line relay 310 whereupon said line relay 310 releases. Relay 310 in releasing places ground upon contact 378 for the purpose of rendering the toll line busy. Relay 405 in operating completes a circuit for the energization of relay 406 over a path extending from ground, winding of relay 406, front contact and left hand armature of relay 405 to grounded battery. Relay 406, in attracting its inner and intermediate right hand armatures, connects conductors 490 and 491 of the link circuit to conductors 492 and 493 of the link circuit respectively, and in attracting its left hand armature completes a circuit for relay 407 over a path extending from grounded battery, winding of relay 407, left hand armature and front contact of relay 406 and left hand normal contacts of relay 409 to ground. Relay 407, in attracting its right hand armatures, interrupts the continuity of the link circuit and connects 1300 cycle current to the line and in attracting its left hand armature completes a circuit for the energization of relay 408 over a path extending from ground, front contact and left-hand armature of relay 407, left-hand normal contacts and winding of relay 408 to grounded battery. Relay 408 thereupon operates and locks up to ground through the left-hand armature and back contact of relay 409. Relay 408 in operating completes a circuit for the operation of relay 410 over a path extending from ground, outer right-hand armature and front contact of relay 408, contact 466 and brush 462 of the switch RSF, winding of relay 410, and back contact and right-hand armature of relay 411 to grounded battery. Relay 410 in operating completes a circuit for stepping magnet 401 over a path extending from grounded battery, winding, armature and back contact of magnet 401, armature and front contact of relay 410, brush 463 and contact 468 of switch RSF, and front contact and outer right hand armature of relay 408 to ground.
- Under the control of magnet 401, the brushes of the switch RSF are moved over their associated contacts until the selected link circuit is found. As soon as the selected link circuit is found, relays 411 and 412 operate over a path extending from ground, winding of relay 412, contact 444 and brush 440 of the switch RSF, outer right-hand armature and back contact of relay 410, left hand normal contacts and winding of relay 411, and outer left-hand armature and front contact of relay 408 to grounded battery. Relays 411 and 412 then lock up, over a circuit including the left hand alternate contacts of relays 411, under control of relay 408. Relay 410 releases and opens the circuit of magnet 401 as soon as relay 411 operates. Relay 411 in operating also completes a circuit at its right-hand alternate contacts for the energization of relay 413, thereby connecting the receiving circuit R^2 to the brushes of the switch RSF.
- As soon as the selected link circuit is found, relay 414 operates over a path extending from grounded battery, winding of relay 414, contact 471 and brush 461 of switch RSF, conductor 598 and back contact and left-hand armature of relay 662 to ground. Relay 414 in attracting its left-hand armature, completes an obvious circuit for relay 409, and in attracting its right-hand armature completes a circuit over a path extending from grounded battery, right-hand armature and front contact of relay 414, contact 470, and brush 460 of switch RSF, winding and left-hand alternate contacts of relay 411, brush 440 and contact 444 of switch RSF and winding of relay 412 to ground for maintaining relays 411 and 412 energized. As soon as relay 409 attracts its left hand armature, it releases relay 407 and opens the locking circuit for relay 408, whereupon said relay 408 releases, thereby opening the original energizing and locking circuit for relays 411 and 412. Relay 409 in attracting its right-hand armature, locks up over a path including the front contact and left-hand armature of relay 405.
- When relay 407 operated, 1300 cycle current was projected over the toll line and received at the receiving circuit R operating relay 262 therein. It will be noted that relay 209, which when operated connects 900 cycle current to the line, is also operated at this time, so that 900 cycle current is also projected over the line circuit and will be received by the receiving circuit R operating relay 264 therein. The 900 and 1300 cycle currents passing into the receiving circuit R^1 do not affect the distant exchange because relay 313 is not operated. Relay 264 is operated over a path extending from grounded battery, armature and back contact of relay 265, winding of relay 264, through the 900 cycle filter 200 f , brush 285 and contact 275 of distributor D, outer left-hand armature and front contact of relay 209, through the source 230 of 900 cycle current, front contact and inner left-hand armature of relay 209, contact 276 and brush 286 of distributor D, through the 900 cycle filter 200 f to ground. The circuit for the energization of relay 262 may be traced as follows: grounded battery, armature and back contact of relay 265, winding of relay 262, through the 1300 cycle frequency filter 200 f^2 , brush 285 and contact 275 of distributor D, through the left-hand winding of repeating coil 290, contact 276 and brush 286 of distributor D,

through the 1300 cycle frequency filter 200 f^2 to ground, current from the 1300 cycle source 450 having been transmitted over an obvious path to the right-hand winding of repeating coil 290 and having been induced into the left-hand winding. Relays 264 and 262 in operating complete a circuit for the energization of relay 115 of the sender switch SW over a path extending from ground, front 10 contact and right-hand armature of relay 264, back contact and right-hand armature of relay 263, right-hand armature and front contact of relay 262, brush 281 and contact 271 of distributor D, inner armature and 15 front contact of relay 241, right-hand armature and back contact of relay 216, right-hand normal contacts and winding of relay 214, front contact and right-hand armature of relay 209, rings of jack 111 and plug 110, 20 outer armature and front contact of relay 105, contact 131 and brush 121 of the cord finder switch CS, brush 140 and contact 160 of sender switch SW and winding of relay 115 to grounded battery.

25 Relay 115 in operating completes a circuit for the motor magnet 102 to advance the brushes of the sender switch SW one step. This circuit may be traced as follows: ground, armature and front contact of relay 30 115, contact 169 and brush 144 of sender switch SW, armature, back contact and winding of motor magnet 102 to grounded battery. Relay 214 also operated in series with relay 115 over the circuit previously traced for the energization of relay 115. Relay 214 in operating locks through its alternate contacts and provides a holding circuit through its outer right-hand contacts for relay 209. In attracting its left-hand 40 armature, relay 214 completes an obvious circuit for relay 216. Relay 216 thereupon operates and locks over a path extending from grounded battery, winding, front contact and left-hand armature of relay 216, and front contact and right-hand armature of relay 202 to ground.

50 As soon as the brushes of the sender switch SW were moved one step, the energizing circuit for relays 214 and 115 was opened thereby causing the release of said relays. Relay 214 in retracting its outer right-hand armature interrupts the holding circuit for relay 209, whereupon said relay 209 retracts its armature thereby rendering the conductors of the line circuit continuous and disconnecting 900 cycle current from the line.

60 It will be assumed that as soon as the operator inserted plug 110 of the cord circuit AA into the jack 111 of the link circuit, she operated keys of the impulse sender S corresponding to the digits representing the number of the desired subscriber at the distant exchange. For the purpose of this description, it will be assumed that the operator has set up the number 120 upon the sender S.

As soon as the key for the hundreds digit is operated, the brush 191 of the distributor D³ in passing over contact 192, will operate motor magnet 102, over a path extending from ground, contact 192 and brush 191 of distributor D³, outer right-hand contacts of the hundreds digit key 1, strapped contacts associated with brush 142 and brush 142 of switch SW and winding of magnet 102 to advance the brushes 140 to 144 inclusive one step.

70 The constantly rotating distributor D³ will then cause three closely succeeding impulses of 900 cycle current to be sent over the line, thereby causing the operation of relay 520 of the receiving circuit R² in the following manner: current from the source of 900 cycle traverses contacts 190 and brush 181 of distributor D³, left-hand contacts of hundreds key 1, contact 161 80 and brush 140 of sender switch SW, conductor 149, brush 121 and contact 131 of cord finder switch CS, front contact and outer armature of relay 105, rings of plug 110 and jack 111, back contact and inner left-hand armature of relay 209, left-hand winding of repeating coil 290, outer left-hand armature and back contact of relay 209, tips of jack 111 and plug 110, inner armature and front contact of relay 105, contact 132 and brush 122 of cord finder switch CS, conductor 128, front contact and outer left-hand armature of relay 108, brush 141 and contact 164 of sender switch SW, right-hand contacts of hundreds key 1, to source 90 100 of 900 cycle ringing current; the current through the left-hand winding of repeating coil 290 will be induced into the right-hand winding of repeating coil 290 and will then flow over the conductors 291 and 292 through the left-hand winding of the repeating coil 380 at the distant office, thereby inducing a corresponding current in the right-hand winding of the repeating coil 380; the current induced into the right-hand winding 105 of repeating coil 380 will cause the operation of relay 520 over a path extending from grounded battery, winding of relay 520, through the 900 cycle frequency filter 500 f , conductor 547, inner armature and front 110 contact of relay 413, brush 441 and contact 445 of switch RSF, front contact and inner right-hand armature of relay 412, conductor 493, inner right-hand armature and front contact of relay 406, conductor 491, back 115 contact and inner right-hand armature of relay 407, brush 332 and contact 372 of switch LFS, back contact and inner right-hand armature of relay 313, through the right-hand winding of repeating coil 380, outer right-hand armature and back contact of relay 313, contact 371 and brush 331 of switch LFS, outer right-hand armature and back contact of relay 407, conductor 490, front contact and outer right-hand armature 120 125 130

of relay 406, conductor 492, intermediate right-hand armature and front contact of relay 412, contact 446 and brush 442 of switch RSF, front contact and outer armature of relay 413, conductor 548, through the 900 cycle frequency filter 500f to ground.

In response to the three impulses transmitted to the relay 520, magnet 522 associated with the switch FS¹ will be energized three times, thereby causing the brushes 530 to 532 inclusive to be moved three steps over their associated terminal banks. In response to the first impulse transmitted to relay 520, relay 521 energizes over an obvious circuit. This relay is preferably of the slow-to-release type and retains its armature attracted during the transmission of the remaining impulses of the series to relay 520. After the last impulse 20 of the series has been transmitted to relay 520, relay 521 releases, thereby causing the operation of counting relay 601 over a path extending from grounded battery, winding and right-hand normal contacts of relay 601, conductor 590, contact 535 and brush 532 of switch FS¹, armature and back contact of relay 521 and back contact and right-hand armature of relay 516 to ground. Relay 601 in operating locks temporarily under control of relay 621 and completes a circuit for the energization of relay 516 over a path extending from grounded battery, winding and left-hand normal contacts of relay 516, conductor 595, front contact and outer right-hand armature of counting relay 601 to ground. Relay 516, in operating, locks over a path extending from grounded battery, winding, left-hand alternate contacts of relay 516, contact 533 and brush 530 of switch FS¹ to ground. Relay 516 in operating, also completes a circuit for the stepping magnet 522 over a path extending from ground, right-hand armature and front contact of relay 516, contact 534 and brush 531 of switch FS¹, armature and back contact and winding of magnet 522 to grounded battery. Magnet 522 thereupon operates and moves the brushes 530 to 532 inclusive of the switch FS¹, one step, whereupon the operating circuit for the motor magnet 522 is interrupted. The switch FS¹ is thus ready for the reception of the next set of impulses.

When the counting relay 601 operated, it completed a circuit for motor magnet 620 of counting switch CT¹ over a path extending from grounded battery, winding, armature and back contact of magnet 620, outer left-hand armature and back contact of relay 621, brush 630 and normal contact of switch CT¹, back contact and left-hand armature of relay 622 and front contact and outer right-hand armature of counting relay 601 to ground. Magnet 620 thereupon operates and moves the brushes 630 to 633 inclusive into engagement with contacts 624 to 627

inclusive respectively. Relay 621 thereupon operates over a path extending from grounded battery, winding and left-hand normal contacts of relay 621, brush 631 and contact 625 of switch CT¹, and front contact 70 and left-hand armature of counting relay 601 to ground. Relay 621 in operating locks under control of relay 662 and in attracting its outer left-hand armature, opens the operating circuit for motor magnet 620, thereby bringing the brushes of the switch CT¹ to rest. Counting relay 601 released when relay 621 operated. Relay 621 in operating also completes a circuit for relay 622 over a path extending from ground, front contact and right-hand armature of relay 621 and winding of relay 622 to grounded battery. Relay 622 in operating disconnects the counting switch CT¹ from the receiving circuit R² and places the counting switch CT² in operative relationship therewith.

At the outer right-hand armature of relay 622 a circuit was extended for motor magnet 663 of the sequence switch SQ, which switch provides for the proper sequence of steps. Motor magnet 663 then operated over a circuit extending from ground, winding of magnet 663, brush 611, and contact 691, of switch SQ, outer right-hand armature 95 and front contact of relay 622, conductor 698, segment 618, brush 619, and segment 617 of constantly operating distributor D⁴ to ground when brush 619 of the distributor D⁴ passes over segment 618 during rotation. The brushes 611 and 680 of the switch SQ, are moved one step due to one impulse being conveyed to magnet 663, whereupon a circuit for pulsing relay 681 is completed over a path extending from grounded battery, winding of relay 681, contact 627 and brush 633 of switch CT¹, contact 636 and brush 680 of switch SQ to ground. Relay 681 in operating causes one impulse to be transmitted over the impulse conductor 699 to the pulsing relay 700 of the selector switch SL over a path extending from ground, segment 617, brush 619 and segment 681' of distributor D⁴, to conductor 699. Relay 681 releases when motor magnet 663 again operates.

The operation of the system for the remaining two digits of the desired number will first be traced before the operation of the selector switch SL is described. As assumed, the next digit of the desired number is 2. It will be noted that as soon as the three 900 cycle impulses were sent over the line conductors to the receiving circuit R², that the brush 191 of the distributor D³ in rotating, again passes over the contact 192, thereby completing a circuit for and delivering an impulse to motor magnet 102, which causes the motor magnet 102 to operate and advance the brushes 140 to 144 inclusive of

the switch SW one step into their fourth position.

In the fourth position of the brushes 140 to 144 inclusive of the sender switch SW, three closely succeeding impulses of 1100 cycle current will be sent over the line circuit to operate the frequency switch FS² of the receiving circuit R², due to the tens key 2 of the sender S being depressed. Relay 540 of the frequency switch FS² will be operated over a path extending from grounded battery, winding of relay 540, through the filter 500f', and thence over conductor 547 and the ring conductor of the line and cord circuit to conductor 149, and thence over brush 140 and contact 162 of sender switch SW, left-hand contacts of tens key 2, brush 182 and contacts 170 of distributor D³, through the source 151 of 1100 cycle current, through the right-hand contacts of tens key 2, contact 165 and brush 141 of sender switch SW, outer left-hand armature and front contact of relay 108, conductor 128, and thence over the path previously traced including the tip conductor of the cord and line circuit to conductor 548, through the 1100 cycle filter 500f¹ to ground. In response to each impulse transmitted relay 540, stepping magnet 542 will advance the brushes 550, 551 and 552 of frequency switch FS² one step. Since for the digit 2 three impulses are transmitted to relay 540, the brushes 550, 551 and 552 will be moved into engagement with contacts 553, 554 and 555, respectively, of frequency switch FS². Upon the first energization of relay 540 in response to the first impulse transmitted thereto, slow to release 541 is energized. Relay 541, being of the slow to release type, maintains its armature attracted during the transmission of the set of impulses to relay 540. When the brushes 550 to 552 inclusive of the switch FS² have been brought to rest upon the terminals 553 to 555 inclusive of the switch FS², relay 541 releases and counting relay 602 will be energized over a path extending from grounded battery, winding and right-hand normal contacts of relay 602, conductor 580, contact 555 and brush 552 of the frequency switch FS², armature and back contact of relay 541 and back contact and right-hand armature of relay 586 to ground. Relay 586 is thereupon energized over a path extending from grounded battery, winding and left-hand normal contacts of relay 586, conductor 595 and front contact and outer right-hand armature of counting relay 602 to ground. Relay 586, in operating, locks up through its left-hand alternate contacts to ground at the contact 553 and brush 550 of switch FS² to ground. As soon as relay 586 attracts its right-hand armature a circuit is completed for stepping magnet 542 over a path extending from ground, right-hand armature and

As soon as relay 586 attracts its right-hand armature a circuit is completed for stepping magnet 542 over a path extending from ground, right-hand armature and

front contact of relay 586, contact 554 and brush 551 of frequency switch FS², armature, back contact and winding of magnet 542 to grounded battery, whereupon magnet 542 is operated and moves the brushes 550 to 70 552 of the switch FS² into engagement with the next set of terminals. The next terminal with which brush 551 comes in contact is open, thereby causing magnet 542 to cease operating. The locking circuit of relay 586 75 is also opened at the next or normal contact whereupon relay 586 releases. The switch FS² is then ready for the reception of the next set of impulses.

When counting relay 602 operated it 80 locked up temporarily under control of relay 641 and completed a circuit for motor magnet 640 of the counting switch CT² over a path extending from grounded battery, winding, armature and back contact of magnet 640, outer left-hand armature and back contact of relay 641, brush 650 and normal contact of switch CT², back contact and left-hand armature of relay 642, front contact and left-hand armature of relay 622, and front contact and outer right-hand armature 85 90 of counting relay 602 to ground.

In response to each impulse transmitted relay 540, stepping magnet 542 will advance the brushes 550, 551 and 552 of frequency switch FS² one step. Since for the digit 2 three impulses are transmitted to relay 540, the brushes 550, 551 and 552 will be moved into engagement with contacts 553, 554 and 555, respectively, of frequency switch FS². Upon the first energization of relay 540 in response to the first impulse transmitted thereto, slow to release 541 is energized. Relay 541, being of the slow to release type, maintains its armature attracted during the transmission of the set of impulses to relay 540. When the brushes 550 to 552 inclusive of the switch FS² have been brought to rest upon the terminals 553 to 555 inclusive of the switch FS², relay 541 releases and counting relay 602 will be energized over a path extending from grounded battery, winding and right-hand normal contacts of relay 602, conductor 580, contact 555 and brush 552 of the frequency switch FS², armature and back contact of relay 541 and back contact and right-hand armature of relay 586 to ground. Relay 586 is thereupon energized over a path extending from grounded battery, winding and left-hand normal contacts of relay 586, conductor 595 and front contact and outer right-hand armature of counting relay 602 to ground. Relay 586, in operating, locks up through its left-hand alternate contacts to ground at the contact 553 and brush 550 of switch FS² to ground. As soon as relay 586 attracts its right-hand armature a circuit is completed for stepping magnet 542 over a path extending from ground, right-hand armature and

682, contact 647 and brush 653 of counting switch CT², contact 687 and brush 680 of the sequence switch SQ to ground. Relay 682, in operating, will cause two impulses to be delivered to the impulse conductor 699 over a path extending from ground, segment 617, brush 619, segments 681' and 682' to the impulse conductor 699.

When the brushes of the sender switch SW are moved into their fifth positions, due to magnet 102 operating after the second set of impulses have been delivered from the distributor D³, two impulses of 1100 cycle current and one impulse of 1300 cycle current will be sent over the line to their respective frequency filters in the receiving circuit R², due to the depression of the units key 0. Relay 540 of the frequency switch 500¹ will be energized twice over a path extending from grounded battery, winding of relay 540 through the frequency filter 500¹, and thence over conductor 547 and the path previously traced to conductor 149, and thence through brush 140 and contact 163 of sender switch SW, left-hand contacts of units key 0, brush 190 and contacts 172 of sender switch SW, through the source 151 of 1100 cycle current, inner right-hand contacts of units key 0, contact 166 and brush 141 of sender switch SW, through the outer left-hand armature and front contact of relay 108, and thence over the path previously traced including conductors 128 and 548, and frequency filter 500¹ to ground.

In response to the two impulses transmitted to relay 540, magnet 542 will be operated twice to move the brushes 550 to 552 inclusive of the frequency switch FS² into engagement with contacts 556 to 558 inclusive respectively. Slow to release relay 541 is energized as previously described on the first impulse being transmitted to relay 540 and deenergizes after the last impulse has been transmitted to said relay 540. Relay 541, in retracting its armature, completes a circuit for relay 511 over a path extending from ground, right-hand armature and back contact of relay 586, back contact and armature of relay 541, brush 552 and contact 558 of frequency switch FS², winding and right-hand normal contacts of relay 511 and back contact and inner right-hand armature of relay 500 to grounded battery.

Closely succeeding the two impulses of 1100 cycle current transmitted to the receiving circuit R², one impulse of 1300 cycle current will be transmitted from the source 152, through the contact 171 and brush 190 of the distributor D³, and thence over a path previously traced to relay 560 of the frequency switch FS³. In response to the impulse transmitted to relay 560, relay 561 and magnet 562 will be energized over obvious circuits. Magnet 562, in operating,

moves the brushes 570, 571 and 572 of the frequency switch FS² into engagement with the contacts 573, 574 and 575 thereof, respectively. Relay 561 deenergizes soon after the impulse is transmitted to relay 560 and a circuit is thereupon completed for relay 503 over a path extending from ground, right-hand armature and back contact of relay 581, back contact and armature of relay 561, brush 572 and contact 575 of switch FS³ and winding of relay 503 to grounded battery.

Counting relay 610 is thereupon energized over a path extending from grounded battery, winding and right-hand normal contacts of relay 610, conductor 596, front contact and right-hand armature of relay 503 and front contact and left-hand armature of relay 511 to ground. Relay 610 thereupon operates and locks temporarily under control of relay 661 and completes a circuit for the operation of relays 581 and 586 of the switches FS² and FS³, respectively, over a path extending from ground, outer right-hand armature and front contact of relay 610, conductor 595, and thence in parallel through the left-hand normal contacts and windings of relays 581 and 586 to grounded battery. Relay 516 is operated at this time but is not locked up. Relays 581 and 586, in operating, lock and complete circuits for motor magnets 562 and 542, respectively, similar to those traced for the motor magnet 522 of the switch FS¹, whereupon the brushes of the switches FS³ and FS² are stepped to a normal position. Relays 581 and 586 thereupon retract their armatures.

Relay 610, in operating, completes a circuit for motor magnet 660 of the switch CT³ over a path extending from grounded battery, winding, armature and back contact of magnet 660, outer left-hand armature and back contact of relay 661, brush 670 and normal contact of switch CT³, front contact and left-hand armature of relay 642, front contact and left-hand armature of relay 622, and front contact and outer right-hand armature of relay 610 to ground. Under the control of magnet 660 the brushes 670 to 673 inclusive are moved over their associated terminals until the terminals corresponding to the operated counting relay are reached, whereupon relay 661 operates over a path extending from grounded battery, winding and inner left-hand normal contacts of relay 661, brush 671 and contact 665 of switch CT³, and front contact and left-hand armature of relay 610 to ground. Relay 661, in operating, locks through its left-hand alternate contacts to ground through the back contact and armature of relay 662. At the outer left-hand armature of relay 661 the circuit for the motor magnet 660 is interrupted.

In attracting its right-hand armature re-

lay 661 prepares a circuit for the motor magnet 663 over a path extending from grounded battery, winding of magnet 663, brush 611 and contact 693 of switch SQ, 5 front contact and right-hand armature of relay 661 to segment 618 of the distributor D⁴. The arm 619 of the distributor D⁴, in rotating, will extend ground from the segment 617 through the arm 619 to the segment 618, whereupon magnet 663 will energize and will step the brushes 680 and 611 of the switch SQ into the next position. Relay 690 will thereupon be energized over a path extending from grounded battery, 10 winding of relay 690, contact 667 and brush 673 of switch CT³, contact 638 and brush 680 of switch SQ to ground. Relay 690, in operating, will cause ten impulses to be delivered to the impulse circuit 699.

20 When the last impulse of the series has been delivered to the impulse circuit 699, magnet 663 will be operated over a path extending from ground, segment 617, brush 619 and segment 618 of distributor D⁴, contact 694 and brush 611 of the sequence switch SQ, winding of motor magnet 663 to grounded battery. Magnet 663, in operating, moves the brushes 680 and 611 of the switch SQ into their fifth positions, whereupon relay 662 is energized over a path extending from ground, brush 680 of switch SQ and its fifth contact, and winding of relay 662 to grounded battery. Magnet 663 again operates over an obvious circuit and moves the brushes 680 and 611 to their sixth position which is a normal position. Relay 662 operates in the fifth position of brush 680 and at its armature and back contact opens the holding circuits for relays 621, 641 and 35 661 of the counting switches CT¹, CT² and CT³, respectively. Relays 621, 641 and 661 thereupon release. Under the control of their respective motor magnets the switches CT¹, CT² and CT³ are then restored to 40 normal position. Switch CT¹ is restored to normal due to magnet 620 operating over a path including winding, armature and back contact of magnet 620, outer left-hand contacts of relay 621 brush 630 and upper contacts of switch CT¹ and the left-hand normal contacts of the counting relays. Switches CT² and CT³ are restored in a 45 similar manner. Relay 662 in operating removes ground from the brush 461 of the finder switch RSF so that relay 414 releases.

50 Relay 414, in retracting its left-hand armature causes the release of relay 409 and in retracting its right-hand armature opens the holding circuit for relays 411 and 412, whereupon said relays 411 and 412 release. Relay 411, in releasing, completes a circuit for relay 410 over a path extending from grounded battery, right-hand armature and back contact of relay 411, winding of relay 410, brush 462, and contact 467

of switch RSF, and back contact and outer right-hand armature of relay 408 to ground. Relay 410 thereupon operates and completes a circuit for motor magnet 401 over a path extending from grounded battery, 55 winding armature and back contact of magnet 401, armature and front contact of relay 410, brush 463 and contact 469 of switch RFS, and back contact and inner right-hand armature of relay 408 to ground. Magnet 401 thereupon operates and advances the brushes of the switch RSF one step. Ground will be present upon the next contact and all succeeding contacts with which brush 463 engages due to conductors (not shown) 60 leading from such contacts to contacts of relays similar to relay 408, so that the brushes of the switch RSF will be restored to normal in the well known manner whereupon relay 410 releases and magnet 401 ceases stepping.

65 After the last impulse of 1300 cycle current for the digit 0 has been delivered to the line circuit, the cord selector switch CS of the sender switch SW will be disassociated from the cord circuit and the continuity of the cord circuit will be restored due to a circuit being completed for motor magnet 102 over a path extending from ground, contact 192 and brush 191 of distributor D³, outer right-hand contacts of units key 0, the strapped contacts associated with brush 142 of the switch SW, brush 142, and winding of magnet 102 to grounded battery. The constantly rotating brush 191 in passing over contact 192, operates magnet 102 over this circuit and moves the brushes of switch SW until a circuit for the key release magnet 118, is completed over a path extending from ground, winding of relay 118, contact 167, and brush 143 of switch SW, brush 123 and contact 133 of switch CS and winding of relay 107 to grounded battery. Relay 118, in operating, restores the depressed sender keys 1, 2 and 0 to normal, and ground being connected to the last two contacts of the bank associated with arm 142, switch SW advances to normal thereby opening the operating circuit for magnet 102, whereupon the switch SW is ready for the next call. Relay 107 is also energized in the circuit just traced and locks up through its left-hand alternate contacts to ground through the front contact and armature of relay 101. Relay 107, in operating, also opens at its left-hand armature and back contact the circuit for relay 105, whereupon said relay 105 releases. In attracting its right-hand armature, relay 107 opens the locking circuit for relay 108, whereupon relay 108 releases. Relay 108, in retracting its armatures, completes a circuit for relay 106 over a path extending from grounded battery, inner left-hand armature and back contact of relay 108, winding of relay 106, brush 125 and 130

contact 135 of switch CS and front contact and right-hand armature of relay 107 to ground. Relay 106, in operating, completes a circuit for magnet 126 over a path extending from grounded battery, winding, armature and back contact of magnet 126, right-hand armature and front contact of relay 106, brush 125 and contact 135 of switch CS, and front contact and right-hand armature of relay 107 to ground. Magnet 126 therefore operates and moves the brushes 120 to 125 inclusive into their normal positions whereupon relay 106 releases and the motor magnet 126 ceases stepping.

15 Referring now to the operation of the switches controlled over the impulse conductor 699, it will be noted that each time the conductor 699 is grounded relay 700 will be energized over a path extending from ground on conductor 699, brush 443 and contact 447 of switch RSF, front contact and outer right-hand armature of relay 412, and winding of relay 700 to grounded battery.

In attracting its left-hand armature, relay 700 completes a circuit for slow-to-release relay 712 and motor magnet 713 over a path extending from ground, left-hand armature and front contact of relay 700, winding of relay 712, winding of magnet 713, first contact of side switch arm 714, and arm 714 to grounded battery. Relay 712 is thereupon energized and completes an obvious circuit for side switch magnet 731. In response to each impulse transmitted to primary magnet 713, the brushes of the selector switch SL are moved one step in a primary direction. After each impulse has been transmitted to relay 700, it releases its armatures, thereby opening the circuit for slow-to-release relay 712. Relay 712 is so designed, however, that it retains its armature attracted during the transmission of a series of impulses and releases its armature at the end of the series of impulses. Relay 45 712 in retracting its armature, opens the circuit for side switch magnet 731, whereupon said magnet causes the side switch arms 714 to 718 inclusive to be moved into their second positions in the well known manner. At 50 side switch arm 717 a circuit is completed for side switch magnet 731 over a path extending from ground, secondary off-normal contacts 789, side switch arm 717 and its second contact and winding of side switch magnet 731 to grounded battery. An obvious self-interrupting circuit is also completed in the second position of the side switch arm 714 for secondary magnet 722.

Under the control of magnet 722, the 60 brushes 740, 741 and 742 of the selector switch SL are moved over their associated contacts until an idle connector switch is found. The test contact of an idle connector switch will have no potential thereon. The test contact of a busy connector switch will

have ground potential thereon, so that side switch magnet 731 will remain energized over a path extending from grounded battery, winding of magnet 731, second contact of side switch arm 717 and arm 717, and brush 742 to ground, as long as brush 742 encounters busy connectors.

As soon as an idle connector is reached, side switch magnet 731 will deenergize, thereby moving the brushes 714 to 718 inclusive into their third positions.

Assuming that connector CC is the one to which the connection has been extended, relays 800 and 801 of connector switch CC will then be energized over a path extending from grounded battery, winding of relay 800, back contact and outer left-hand armature of relay 860, conductor 851 terminal 744, brush 741, of switch SL, side switch arm 716 and its third contact, back contact and right-hand armature of relay 700; outer armature and back contact of relay 721, winding of relay 701, back contact and inner armature of relay 721, third contact of side switch arm 715 and side switch arm 715, brush 740, terminal 743, conductor 850, inner left-hand armature and back contact of relay 860 and winding of relay 801 to ground. Relay 801 in operating completes an obvious circuit for relay 802 which is preferably of the slow to release type. Relay 802 in operating locks to ground at the third contact side switch arm 717. Relay 701 will also be energized in the circuit just traced.

In response to the next set of impulses transmitted over the impulse conductor 699, relay 700 will be energized twice, thereby causing two interruptions in the circuit of the relays 701, 800 and 801, whereupon these relays retract their armatures a number of times corresponding to the interruptions in the circuit of these relays. Primary magnet 810 of the connector switch CC is energized each time the relay 800 retracts its armature over a path extending from ground, armature and back contact of relay 800, right-hand armature and front contact of slow-to-release relay 802, winding of slow-to-release relay 803, back contact and outer armature of relay 804, winding of magnet 810 and first contact of side switch arm 831 and side switch arm 831 to grounded battery. Relay 803 is energized upon the first impulse of current therethrough and in attracting its armature completes a circuit for side switch magnet 805 over a path extending from ground, armature and front contact of relay 803 and winding of side switch magnet 805 to grounded battery. Magnet 805 in attracting its armature disconnects relay 835 from the test brush 822 and the side switch arm 830. Relay 803 is preferably of the slow-to-release type and retains its armature attracted during the

transmission of a set of impulses, but releases its armature after the last impulse of a series.

As soon as the first set of impulses has been transmitted to the connector switch CC, relays 701, 800 and 801 again attract their armature for a short interval, thereby interrupting the circuit for relay 803. Relay 803 thereupon retracts its armature, thereby opening the circuit for side switch magnet 805, whereupon said magnet causes the movement of the side switch brushes 830 and 831 into their second positions.

In response to the next set of impulses, the circuit of relay 800 will be interrupted ten times, whereupon ten impulses will be delivered to the secondary magnet 811 over a path extending from ground, armature and back contact of relay 800, right-hand armature and front contact of relay 802, winding of relay 803, back contact and armature of relay 804, winding of secondary magnet 811, second contact of side switch arm 831 and side switch arm 831 to grounded battery. In response to the actuations of secondary magnet 811, the brushes 820 to 822 will be moved ten steps over their associated contacts into engagement with the terminals of the desired line. Relay 803 will be energized upon the first impulse and will remain energized until after the last impulse has been delivered to the secondary magnet 811, whereupon said relay 803 will retract its armature thereby opening the operating circuit for side switch magnet 805.

Assuming that the called line is idle, side switch magnet 805 will retract its armature, due to the absence of ground potential on test terminal 825, thereby moving the side switch arms 830 and 831 of switch CC into their third positions. Relay 835 of the connector CC and cut off relay 826 of the called line will then be energized over obvious circuits due to ground being connected to the third position of the side switch arm 830. Relay 835, in attracting its armatures, extends the conductors 840 and 841 through to the terminals 823 and 824, respectively of the called line. The cut off relay 826 of the called line performs the well-known function of preventing the non-numerical switch at the called station from operating when the called station removes the receiver from the switch hook.

When the last set of impulses has been delivered to the connector switch, the brushes thereof will be in engagement with the terminals of the desired line and as heretofore described relay 412 will release and relays 701, 800 and 801 will again energize. Relay 704 will then energize over a path extending from grounded battery, right hand armature and back contact of relay 711, winding of relay 704, front contact and armature of relay 701, side switch arm 718 and its

third contact, and left hand armature and back contact of relay 412. Relay 704 in operating completes a circuit for relay 705 through its outer left hand contacts and a circuit for relay 720 through its inner right hand contacts. Relay 705 in operating renders the link discontinuous and connects 70 and 1100 cycle current to that portion of the link circuit extending to the originating exchange for the purpose of operating an operator's supervisory signal as hereafter described. Relay 720 in operating locks up under control of relay 428.

The operator at the originating exchange may now be signalled for the purpose of 80 informing her that the called station may be signalled. A supervisory lamp 159 is provided at her position which will be actuated in the manner hereafter described. Relays 307 and 416 operate when the constantly rotating distributor D¹ reaches the contacts with which the leads from these relays are connected. The circuit for these relays may be traced as follows: grounded battery, winding of relay 307, brush 344 and contact 364, of distributor D¹, outer left-hand armature and back contact of relay 313, contact 373 and brush 333 of switch LFS, left-hand normal contacts and winding of relay 416, and front contact and left-hand armature of relay 720 to ground. Relay 416 locks up temporarily over a path extending from grounded battery, inner right-hand armature and back contact of relay 428, left-hand alternate contacts and winding of relay 416, and front contact and left-hand armature of relay 720 to ground. During the next cycle of the distributor D¹, relay 428 is operated over a path extending from ground, left-hand armature and front contact of relay 720, front contact and right-hand armature of relay 416, winding and left-hand normal contacts of relay 428, brush 333 and contact 373 of switch LFS, back contact and outer left-hand armature of relay 313, contact 364, and brush 344 of distributor D¹, and winding of relay 307 to grounded battery. Relay 428, in operating locks up momentarily under control of relay 720, releases relays 416 and 720 and also completes a circuit for relay 711 and 723 over a path extending from ground, outer right-hand armature and front contact of relay 428, thence in parallel thru the left-hand normal contacts and winding of relay 711 to grounded battery and the left hand normal contacts and winding of relay 723 to grounded battery. Relay 711 thereupon operates and locks up through its left-hand alternate contacts the intermediate right-hand armature and back contact of relay 720, the front contact and armature of relay 701, side switch arm 718 and its third contact to ground at the back contact and left-hand armature of relay 412. Relay 711, 130

in operating, opens the holding circuit for relay 704, whereupon said relay 704 releases, causing the release of relay 705.

In this manner the signal from the 5 coming end is passed over the trunk to the outgoing end during two cycles of the distributor D¹. In fact as before stated, all supervisory signals are determined by the time the distributor takes to complete two 10 cycles.

In this manner 900 and 1100 cycle currents from a source 781 are passed over the line circuit to the originating exchange and are received by the receiving circuit R, whereupon relays 264 and 263 of the receiving circuit R are operated over a path traceable from source of 900 and 1100 cycle current 781, back contact and outer left-hand armature of relay 725, back contact and outer armature of relay 730, front contact and inner armature of relay 705, condenser 771, back contact and inner right-hand armature of relay 412, conductor 493, inner right-hand armature and front contact of relay 406, conductor 491, back contact and inner right-hand armature of relay 407, brush 332 and contact 372 of switch LFS, back contact and inner right-hand armature of relay 313, through the right-hand winding of repeating coil 380, outer right-hand armature and back contact of relay 313, contact 371 and brush 331 of switch LFS, outer right-hand armature and back contact of relay 407, conductor 490, front contact and intermediate right-hand armature of relay 406, conductor 492, intermediate right-hand armature and back contact of relay 412, condenser 770, outer armature and front contact of relay 705, inner armature and back contact of relay 730, and inner left-hand armature and back contact of relay 725 to source 781 of 900 and 1100 cycle current; the current through the right-hand winding of coil 380 is induced into the left-hand winding of repeating coil 380 and this current traversing conductors 291 and 292 and the right-hand winding of repeating coil 290, induces a corresponding current in the left-hand winding of repeating coil 290; this induced current, then passes through the contact 275 and brush 285 of the distributor D, and thence in parallel, one path extending through the filter 200^f and winding of relay 264 to grounded battery at the back contact and armature of relay 265, and the other path extending through the filter 200^f and the winding of relay 263 to grounded battery at the back contact and armature of relay 265, and thence from ground through the filters 200^f and 200^f in parallel, through the brush 286 and contact 276 of distributor D to the secondary winding of repeating coil 290. Due to the fact that relay 307 is operated each time the brush 344 engages the contact 364 while the signal is being sent

the signalling currents do not affect receiving circuit R¹. Relays 264 and 263 of receiving circuit R operate and complete a circuit for the operation of relay 201 over a path extending from ground, front contact 70 and left-hand armature of relay 264, front contact and inner left-hand armature of relay 263, brush 283 and contact 273 of distributor D inner right-hand armature and front contact of relay 250 and normal contacts and winding of relay 201 to grounded battery.

Relay 201 thereupon operates and locks through its left-hand alternate contacts and through the back contact and armature of relay 226, armature and back contact of relay 212 to ground at the armature and front contact of relay 202. Relay 201, in operating, connects ground through relay 212 to the sleeve of the jack 111 and so reduces the resistance in the sleeve of the 85 cord and line circuit that marginal relay 103 of the cord circuit operates. Relay 212, being marginal does not operate at this time. Relay 201 in operating locks up under control of relay 226. Relay 103 of the cord 90 circuit in operating completes an obvious circuit for the lamp signal 159 which lights and serves as a signal to the operator that the connection is completed and that ringing current may be impressed on the line. 95

The operator then depresses the ringing key 139 of the cord circuit AA, thereby simultaneously applying 900 and 1100 cycle currents to the line conductors, which currents are received by the receiving circuit 100 R¹ and cause the operation of relays 301 and 302. The path for the energization of these relays may be traced as follows: from source 150 of 900 and 1100 cycle current, through the upper alternate contacts of key 105 139, back contact and inner armature of relay 105, tips of plug 110 and jack 111, back contact and outer left-hand armature of relay 209, through the primary winding of repeating coil 290, inner left-hand armature 110 and back contact of relay 209, rings of jack 111 and plug 110, outer armature and back contact of relay 105, and lower alternate contacts of key 139 to the source 150 of 900 and 1100 cycle current; current passing 115 through the primary winding of repeating coil 290 induces current in the secondary winding thereof which traverses conductors 291 and 292 and the primary winding of repeating coil 380 at the distant office, current flowing through the left-hand winding of repeating coil 380 induces current in the right-hand winding thereof, which passes over contact 361 and brush 341 of distributor D¹, and thence in parallel, one path extending through filter 300^f and the winding of relay 301 to grounded battery at the back contact and armature of relay 307, and the other path extending through the filter 300^f and winding of relay 302 to grounded bat- 130

tery at the back contact and armature of relay 307; the return path of this current being from ground through the filters 300f and 300f¹ in parallel, and thence over brush 340 and contact 360 of distributor D¹ to the secondary winding of repeating coil 380.

Relays 301 and 302 thereupon operate and complete a circuit for relay 720 over a path extending from ground, front contact and right-hand armature of relay 301 front contact and inner right-hand armature of relay 302, brush 343 and contact 363 of distributor D¹, inner right-hand armature and back contact of relay 315, contact 370 and brush 330 of switch LFS, and right-hand normal contacts and winding of relay 720 to grounded battery. Relay 720, in operating, locks up under control of relay 428. Relay 720, in attracting its outer right-hand armature, completes an obvious circuit for relay 721. Relay 721 then operates and connects ground to the tip and ring conductors 850 and 851, respectively, whereupon relay 801 of the connector CC releases due to its being short circuited. Relay 800 remains energized. Relay 801, in retracting its armatures, completes a circuit for relay 836 over a path extending from ground, armature and front contact of relay 800, back contact and outer armature of relay 801, back contact and right-hand armature of relay 860, winding of relay 836, third contact and side switch arm 831 to grounded battery. Relay 836, in energizing, connects a source of ringing current 842 to the conductors 840 and 841, whereupon the station of the called line is signalled over a path extending from source of current 842, front contact and inner armature of relay 836, conductor 841, inner armature and front contact of relay 835, brush 821 and terminal 824 of switch CC, through the substation loop, terminal 823 and brush 820 of switch CC, front contact and outer armature of relay 835, outer armature and front contact of relay 836 to ground.

The ringing current from the source 842 is impressed upon the called line for a period representing the time required for the distributor D¹ to complete two cycles and operate relays 416, 428 and 720 as hereinbefore described. Relay 720 in releasing releases relay 721. If the operator desires to continue the ringing, it is necessary for her to maintain ringing key 139 actuated for the desired period.

When the called party answers, relay 860 of the connector switch CC operates over a path extending from ground, left-hand winding of relay 860, outer left-hand armature and back contact of relay 836, conductor 840, outer armature and front contact of relay 835, brush 820 and terminal 823 of switch CC, through the called substation

loop, terminal 824 and brush 821 of switch CC, front contact and inner armature of relay 835, conductor 841, inner left-hand armature and back contact of relay 836 and right-hand winding of relay 860 to grounded battery. Relay 860, in attracting its left-hand armatures, disconnects the line relays 800 and 801 from the connector switch CC, whereupon said relays are released. When line relays 800 and 801 are disconnected from the connector circuit, relay 701 is de-energized and in retracting its armature opens the holding circuit for relay 711, causing the release of said relay 711. Relay 724 thereupon operates over a path extending from grounded battery, winding of relay 724, back contact and armature of relay 701, side switch arm 718 and its third contact, and back contact and left-hand armature of relay 412 to ground. Relay 725 also operates when relay 701 releases over a path extending from grounded battery, right-hand armature and back contact of relay 723, winding of relay 725, back contact and outer right-hand armature of relay 704, back contact and armature of relay 701, side switch arm 718 in its third position, and back contact and left-hand armature of relay 412 to ground. Relay 725 in operating completes a circuit through its inner right-hand contacts for relay 705 and through its outer right-hand contacts for relay 720. Relay 720 then locks under control of relay 428 and 900 and 1100 cycle currents are sent over the line for two cycles of the distributor in the manner similar to that hereinbefore described. When relay 723 operates relay 725 releases causing the disconnection of the 900 and 1300 cycle current. Relay 723 in operating locks under control of relay 701.

Relay 725 in operating connects 900 and 1300 cycle current simultaneously for two cycles of the distributor to the line over a path extending from source 782, of 900 and 1300 cycle current, front contact and outer left-hand armature of relay 725, back contact and outer armature of relay 730, front contact and inner armature of relay 705, condenser 771, back contact and inner right-hand armature of relay 412, conductor 493, inner right-hand armature and front contact of relay 406, conductor 491, back contact and inner right-hand armature of relay 407, brush 332 and contact 372 of switch LFS, back contact and inner right-hand armature of relay 313, through the right-hand winding of repeating coil 380, outer right-hand armature and back contact of relay 313, contact 371 and brush 331 of switch LFS, outer right-hand armature and back contact of relay 407, conductor 490, front contact and intermediate right-hand armature of relay 406, conductor 492, intermediate right-hand armature and back contact of relay 412, condenser 770, outer armature and front contact

of relay 705, inner armature and back contact of relay 730, and inner left-hand armature and front contact of relay 725 to source 782 of 900 and 1300 cycle current. The current passing through the right-hand winding of coil 380 will induce a corresponding current in the left-hand winding thereof which, in traversing the conductors 291 and 292 extending to the originating exchange, 10 will induce a corresponding current in the left-hand winding of repeating coil 290; this current will then pass over contact 275 and brush 285 of distributor D, and thence in parallel, one path extending through the filter 200^f and winding of relay 264 to grounded battery at the back contact and armature of relay 265, and the other path extending through the filter 200^{f2} and the winding of relay 262, and thence to ground- 15 ed battery at the back contact and armature of relay 265; the return path for this current extending from ground through the filters 200^f and 200^{f2} in parallel, through brush 286 and contact 276 of distributor D 20 to the repeating coil 290. 25

Relays 264 and 262 thereupon operate and complete a circuit for the operation of relay 226 over a path extending from ground, front contact and right-hand armature of relay 264, back contact and right-hand armature of relay 263, right-hand armature and front contact of relay 262, brush 281 and contact 271 of distributor D, inner armature and front contact of relay 241, right-hand armature and front contact of relay 216, and winding of relay 226 to grounded battery. Relay 226 thereupon operates and in attracting its armature opens the locking circuit for relay 201, whereupon the disconnection of the circuit through relay 212 changes the sleeve resistance to such a degree that marginal relay 103 of the cord circuit AA releases, causing the extinguishment of the signal lamp 159, thereby indicating to the operator that the called subscriber has answered. Upon the completion of two cycles of distributor D¹ relay 723 energizes as previously described and opens the circuit of relay 725 to disconnect current source 782.

50 When the called subscriber restores his receiver, relay 860 releases, thereby again connecting relays 800 and 801 to the tip and ring conductors, respectively, of the trunk circuit, thereby causing the energization of
55 relays 800 and 801 and the bridged relay 701. Relay 701 in attracting its armature releases relay 723 and again completes the circuit for relay 704. Relay 704, in attracting its outer left-hand armature, completes
60 a circuit for relay 705, whereupon 900 and 1100 cycle currents are simultaneously sent over the circuit in a manner similar to that previously described, whereupon relays 264 and 263 of the receiving circuit are energized and in attracting their armatures
65

again cause the energization of relay 201 over the path previously traced. Relay 201, in operating, again causes the lamp signal 159 to light in the manner herein before described. The lighting of the signal lamp 159 indicates to the operator that the called party has disconnected. 70

The operator, noting the disconnect signal, may remove the plug 110 of her cord circuit AA from the jack 111 of the toll line circuit whereupon all apparatus of the cord circuit will be restored to normal position and relay 202 of the trunk circuit will be deenergized. Relay 202 in retracting its armature, causes the release of relay 210. Relay 210, in releasing, connects 1100 and 1300 cycle current to the trunk line for causing the release of all operated apparatus in the established connection. The 1100 and 1300 cycle current is prevented from affecting the receiving circuit R due to the operation of relay 265, each time the brush 282 of the distributor D¹ passes over the contact 272 corresponding to the toll line circuit, herein described. Relays 302 and 303 of the receiving circuit R¹ are operated, however, over a path extending from the source 251 of 1100 and 1300 cycle current, intermediate armature and back contact of relay 210, intermediate right-hand armature and front contact of relay 225 thence through the repeating coil 290, outer right-hand armature and front contact of relay 225 and to source 257 through the outer right-hand armature and back contact of relay 210. Current is induced from repeating coil 290 through repeating coil 380, thence through contact 361 and brush 341 of the distributor D¹, and thence in parallel one path extending through 1100 cycle filter 300¹, winding of relay 302 to grounded battery at the back contacts of relay 307 and the other path extending through the filter 300², and winding of relay 303 to grounded battery at the back contact and armature of relay 307 and thence to ground, through the filters 300¹, 300² in parallel, thence over brush 340 and contact 360, to repeating coil 380. Relays 302 and 303, in operating, complete a circuit for release relay 312, over a path extending from grounded battery, winding of relay 312, back contact and left hand armature of relay 315, contact 362 and brush 342 of distributor D¹, front contact and outer right-hand armature of relay 302, and right-hand armature and front contact of relay 303 to ground. Relay 312, in operating, opens the holding circuit for cutoff relay 311 and relay 405 whereupon said relays 311 and 405 release. Relay 405, in releasing, opens the holding circuit for relay 406. Relay 406, in releasing completes a circuit for release magnet 735 of the switch SL extending from ground, outer right-hand armature and back contact of relay 406, off

normal contacts 736 and winding of magnet 735 to grounded battery. Magnet 735 thereupon operates and locks through its own contacts and causes the restoration of the switch SL in the manner well known in the art. When the switch SL returns to normal, the contacts 736 open thereby releasing magnet 735.

Restoration of the switch SL to normal position, causes the release of relays 800 and 801 of the connector switch CC and the opening of the locking circuit for slow-to-release relay 802. Relay 802 releases and completes a circuit for release magnet 834 over a path extending from ground, armature and back contact of relay 800, right-hand armature and back contact of relay 802, off normal contacts 833 of switch CC and winding of magnet 834 to grounded battery.

Magnet 834 thereupon operates and causes the restoration of the connector switch CC to normal in the manner well known in the art.

If the called subscriber flashes, the relay 860 will be intermittently actuated, thereby causing the intermittent actuation of relays 800 and 801 of the connector CC and relay 701 of the selector SL. Relay 724 is operated at the first deenergization of relay 701 and it being of the slow to release type, does not deenergize due to the intermittent energization of relay 701. Relay 704 locks under control of relays 711 and 724 during the flashing and in operating completes the circuit for relay 705.

Relay 730 will also be intermittently energized, when the subscriber flashes, over a path from grounded battery, winding of relay 730, front contact and outer right-hand armature of relay 704, back contact and armature of relay 701, side switch arm 718 and its third contact, and back contact and left-hand armature of relay 412 to ground.

Relay 730, in operating, connects 1100 and 1300 cycle current simultaneously for two cycles of the distributor D to the receiving circuit R, causing the operation of relays 263 and 262 thereat in a manner similar to that previously described for other relays of the receiving circuit R. Relays 263 and 262, in operating, complete a circuit for the energization of relay 220 over a path extending from ground, front contact and left-hand armature of relay 262, outer left-hand armature and front contact of relay 263, brush 284 and contact 274 of distributor D, outer right-hand armature and front contact of relay 250, left-hand normal contacts and winding of relay 220 to grounded battery. Relay 220, in operating, locks up under the control of relay 212 and connects the interrupter 228 to the sleeve circuit which intermittently operates relay 103 and thereby causes the flashing of the lamp signal 159. Marginal relay 212 does not operate in this flashing circuit.

The operator noting this flashing signal may actuate the listening key K, thereby connecting battery through the contacts 138 of the key K and through the resistance 137 to the sleeve circuit which increases the current flowing through the marginal relay 212 to such an extent that said relay 212 energizes, causing the release of relay 220 and the disconnection of interrupter 228 from the sleeve circuit. Relay 103 deenergizes due to the shunt circuit established therearound by the operation of contact 138 of key K causing the extinguishment of lamp signal 159.

In case the called line is busy, the ground present upon the test contact thereof when the side switch 830 is in its second position, causes the operation of relay 804 which connects a source of busy tone 832 to the connector. The operator, not receiving a ringing signal within the usual time, actuates listening key LK to connect the receiver across the line and upon receiving the busy tone disestablishes the connection.

As heretofore stated, the toll trunk line 90 herein disclosed is of the two-way type and a brief description will now be given of the manner in which a call may be extended from the distant exchange, such as BB to the originating exchange such as DD over 95 the toll line. To simplify the drawing, the cord circuit, cord selector switch CS and sender switch SW used in extending calls from exchange BB to the exchange DD shown in Fig. 1 of the drawings have been 100 omitted. Relays shown in Fig. 2 and Fig. 3 of the drawings having like functions are designated with like letters as hereinbefore stated. The blank rectangle WA shown in Fig. 2 of the drawings includes circuits and apparatus as shown in Figs. 4 to 8 inclusive of the drawings and that portion of the drawing shown in Fig. 3 enclosed within the dotted line shown thereon.

The insertion of plug 110 into jack 327 110 of the trunk circuit at the exchange BB causes the energization of sleeve relay 101 of the cord circuit and relay 325 of the toll line. Relay 103 being marginal does not operate. Relays 104 and 105 of the cord 115 circuit thereupon operate, the latter relay rendering the cord circuit discontinuous and associating the switch CS with the calling plug 110. Relay 106 then operates causing the motor magnet 126 to operate and extend the calling plug to the sender switch SW. Relay 325 of the toll line, in operating, causes the energization of relays 322 and 318. Relay 322, in operating, connects 900 cycle current to the line so that when the 120 brushes of distributor D at the exchange DD engage contacts of this line, relay 264 operates and causes the operation of the line relay at the exchange DD, similar to the line relay 310 at the exchange BB. Relay 125 130

318, in operating, completes a circuit for relays 317, 313 and 315 at the exchange BB. Relay 317, in operating, locks up under control of relay 314. Relay 313, in operating, prevents the 900 cycle current from affecting the receiving circuit. Relay 315, in operating, connects the relays 323 and 324 in operative relationship with the distributor D¹ and disconnects the line relay 310 from operative relationship with the distributor D¹ thereby preventing the operation of the line relay at the exchange from which the call is being made.

It is believed that the above brief description in addition to the foregoing description will suffice to clearly indicate how a call may be established from the exchange BB to the exchange DD and how the various supervisory signals may be transmitted over the line and disconnection effected by employment of a plurality of different current frequencies.

It will be apparent from Fig. 1 of the drawings, what combinations of frequencies are employed in sending the various digits of the decimal system of notation, for example, to cause the automatic switch to take four steps, two 900 and one 1100 cycle impulses are utilized.

It is also not deemed necessary to increase the descriptive matter of the specification by describing when relays 500, 501, 502, 505 and 513 operate in response to impulses delivered to the switches FS¹, FS² and FS³ as it is believed that their operation will be readily apparent to those skilled in the art.

Although use has been made of the frequencies 900, 1100 and 1300 in this specification, it is to be understood that the invention is not limited thereto and that other frequencies preferably within the voice range may be employed. It is desirable to employ frequencies within the voice range since the transmission lines, including the repeating coils and other repeating apparatus, are designed to efficiently transmit currents within such range.

What is claimed is:

1. In a telephone exchange system, a first exchange, a second exchange, a line extending between said exchanges, means including said line and automatic switches for connecting stations of said exchanges, a plurality of sources of currents of different frequencies, means for selectively applying different combinations of said sources to said line and means responsive to each combination of frequencies to cause a corresponding directive movement of said switches.

2. In a telephone exchange system, a first exchange, a second exchange, a line extending between said exchanges, means including a cord circuit, said line and automatic switches for connecting stations of said ex-

changes, a supervisory signal in said cord circuit, a plurality of sources of current of different frequencies, means for transmitting combinations of impulses of different frequencies over said line, means responsive to each combination of frequencies to cause a corresponding directive movement of said automatic switches, and means for automatically applying a plurality of said frequencies to said line to control said supervisory signal.

3. In a telephone system, a calling station at one exchange, a called station at another exchange, means including a cord circuit, a line circuit and automatic switches for connecting said stations, a supervisory signal in said cord circuit, a plurality of sources of current of different frequencies, and means for controlling the operation of said switches, said supervisory signal, and the application of ringing current to the called line by means of combinations of a plurality of said sources.

4. In a telephone system, a calling station at one exchange, a called station at another exchange, means including a cord circuit, a line circuit and automatic switches for connecting said stations, a supervisory signal in said cord circuit, and means for controlling the operation of said switches, the supervision of an established connection, and the releasing of said switches by combinations of a plurality of frequencies within the voice range.

5. In a telephone system, an automatic switch, a plurality of sources of current of different frequencies, means for transmitting sets of impulses consisting of different combinations of said frequencies and means responsive to each set of impulses to cause the actuation of said switch in a corresponding directive movement.

6. In a telephone system, an automatic switch, a plurality of sources of voice frequency currents, means for transmitting impulses in different combinations for controlling the operation of said switch, said impulses emanating from a plurality of said sources of current, a release magnet for said switch, and means for controlling the actuation of said release magnet by means of a plurality of said frequencies.

7. In a telephone system, an originating exchange, a distant exchange, subscribers' lines terminating in each of said exchanges, a plurality of two-way trunk lines extending between the exchanges each of said trunk lines terminating at each of said exchanges in outgoing and incoming terminals, said incoming terminals being accessible to automatic switching mechanism for extending connections to said subscribers' lines terminating in said associated exchange, means at each exchange for seizing the outgoing terminals of one of said trunk lines and for

thereafter transmitting impulses of a plurality of frequencies over said trunk line for controlling the switching mechanism in which said trunk line terminates at said other exchange, and means at each exchange for transmitting impulses of a plurality of frequencies over said trunk lines for supervising an established connection.

8. In a telephone system, an originating exchange, a distant exchange, a subscriber's line terminating in each of said exchanges, a plurality of two-way trunk lines extending between said exchanges, each of said trunk lines terminating at each of said exchanges in outgoing and incoming terminals, said incoming terminals being accessible to automatic switching mechanism for extending connections to said subscriber's lines terminating in said associated exchange, means at each exchange for seizing the outgoing terminals of one of said trunk lines and for thereafter transmitting impulses of a plurality of different frequencies over said trunk line for controlling the switching mechanism in which said trunk line terminates at said other exchange.

9. In a telephone system, an originating exchange, a distant exchange, a subscriber's line terminating in each of said exchanges, a plurality of two-way trunk lines extending between said exchanges each of said trunk lines terminating at each of said exchanges in outgoing and incoming terminals, said incoming terminals being accessible to automatic switching mechanism for extending connections to said subscriber's lines terminating in said associated exchange, means at each exchange for seizing the outgoing terminals of one of said trunk lines and for thereafter transmitting impulses of a plurality of different frequencies over said trunk line for controlling the switching mechanism in which said trunk line terminates at said other exchange, a supervisory signal, and means at each exchange for simultaneously applying current of two different frequencies to said trunk line for controlling the said supervisory signal.

10. In a telephone system, a first exchange, a second exchange, a subscriber's line terminating at said second exchange, a plurality of trunk lines extending between said exchanges, automatic switching mechanism at said second exchange accessible to said trunk line for extending connections from said trunk line to said subscriber's line, an impulse repeater at said second exchange means for associating said repeater with said trunk lines, and impulse transmitting means at said originating exchange for transmitting impulses of a plurality of frequencies over any one of said trunk lines to said repeater for setting said switching mecha-

nism in each of its directive movements up on the terminals of the desired line. 65

11. In a telephone system, a first exchange, a second exchange, a subscriber's line terminating at said second exchange, a plurality of trunk lines extending between said exchanges, automatic switching mechanism at said second exchange accessible to said trunk lines for extending connections from said trunk lines to said subscriber's line, an impulse repeater at said second exchange 70 common to said trunk lines, means for associating said repeater with any of said trunk lines, impulse transmitting means at said originating exchange for transmitting impulses of a plurality of frequencies over any 75 one of said trunk lines to said repeater for setting said switching mechanism upon the terminals of the desired line, a supervisory signal at said first exchange, means operated when the switching mechanism is set upon 80 the terminals of the desired line for simultaneously applying a plurality of frequencies to said trunk line for causing the operation of said supervisory signal. 85

12. In a telephone system, a first exchange, 90 a second exchange, a subscriber's line terminating at said second exchange, a plurality of trunk lines extending between said exchanges, automatic switching mechanism at said second exchange accessible to said trunk 95 lines for extending connections from said trunk lines to said subscriber's line, an impulse repeater at said second exchange common to said trunk lines, means for associating said repeater with any of said trunk 100 lines, impulse transmitting means at said originating exchange for transmitting impulses of a plurality of frequencies over any one of said trunk lines to said repeater for setting said switching mechanism upon the 105 terminals of the desired line, a supervisory signal at said first exchange, and means operated when the called subscriber responds for simultaneously applying to said line a plurality of frequencies for causing the actuation of said supervisory signal. 110

13. The method of extending a call to a called station and of supervising a connection thereto which comprises transmitting and selectively receiving predetermined combinations of current impulses of different frequencies and translating each combination into a corresponding switching movement. 115

14. The method of supervising a connection with a called station which comprises simultaneously transmitting and simultaneously receiving currents of different frequencies and translating said frequencies into a corresponding supervisory function. 120

15. The method of extending a connection to a numbered called station which comprises selectively transmitting different com- 125

binations of current impulses of different frequencies for each digit of the number of the called station and selectively receiving the impulses and translating each combination into a corresponding switching movement.

16. The method which comprises transmitting combinations of equal numbers of current impulses, receiving said impulses and translating said combinations into sets of current impulses varying in number and causing each of said set of impulses to produce a corresponding switching movement.

17. In a telephone system, an operator's position, a signal thereat, a trunk circuit terminating at the operator's position, a called station, means including automatic switches for extending a connection from said position over said trunk line to said called station, a plurality of sources of current, and means controlled by said called station for applying a combination of impulses from said source to said trunk line for controlling said signal.

18. In a telephone system, a calling and a called station, automatic switches for building up a connection between said stations, an auxiliary switch, and a supervisory signal controlled by said called station and said auxiliary switch.

19. In a telephone exchange system, a first exchange, a second exchange, a two-wire trunk circuit extending between said exchanges, a calling station connected with said first exchange, a called station connected with said second exchange, means including automatic switching apparatus for connecting said stations over said trunk circuit, an auxiliary step-by-step switch at said first exchange, sources of alternating current at said second exchange, means controlled by the called station for applying said sources to said line, a supervisory signal, and means associated with said auxiliary switch responsive to current from said sources and cooperating with said auxiliary switch to control said supervisory signal.

20. In a telephone system, a line circuit, a station connected thereto, a link circuit for connection with said line circuit, a supervisory signal in said link circuit, means controlled by said station for connecting current to said line for controlling said signal, and a continuously rotating device to

limit the application of such current to a certain period.

21. In a telephone exchange system, a line circuit, a cord circuit for connecting therewith, a plurality of sources of alternating current of different frequencies, a plurality of impulse senders for selecting currents of said frequencies, a plurality of cord selectors operable upon connection of said cord circuit with said line circuit for associating an idle one of said impulse senders with said cord circuit, means also responsive to the connection of said cord circuit with said line circuit to connect one of said sources to said line circuit independently of said impulse senders, a receiving circuit for current transmitted from said source over said line circuit, a continuously rotating distributor for connecting said receiving circuit to said line circuit, a link circuit, a line finder for connecting said link circuit to said line circuit, means controlled by said receiving circuit for starting said line finder, a second receiving circuit for connection with said link circuit upon the connection of said line circuit with said link circuit, means responsive to the connection of said second receiving circuit with said link circuit to connect another of said sources to said line circuit independently of said impulse senders, a third receiving circuit, a second continuously rotating distributor for connecting said third receiving circuit to said line circuit, means responsive to currents from said first and second selected sources to render said selected sender active, a third continuously rotating distributor for connecting the selected frequencies to said sender, a switch for determining the order in which impulses are transmitted over the line from said impulse sender, means controlled by the second mentioned receiving circuit for translating said impulses into direct current impulses, means for storing said direct current impulses, a called station, a fourth continuously rotating distributor for transmitting said stored impulses, and a switching mechanism responsive to said transmitting impulses to connect said called station to said line.

22. In a telephone system, a calling and a called station, automatic switches for building up a connection between said stations, an auxiliary switch, and a supervisory signal controlled by said called station and said auxiliary switch.

23. In a telephone exchange system, a first exchange, a second exchange, a two-wire trunk circuit extending between said exchanges, a calling station connected with said first exchange, a called station connected with said second exchange, means including automatic switching apparatus for connecting said stations over said trunk circuit, an auxiliary step-by-step switch at said first exchange, sources of alternating current at said second exchange, means controlled by the called station for applying said sources to said line, a supervisory signal, and means associated with said auxiliary switch responsive to current from said sources and cooperating with said auxiliary switch to control said supervisory signal.

24. In a telephone system, a line circuit, a station connected thereto, a link circuit for connection with said line circuit, a supervisory signal in said link circuit, means controlled by said station for connecting current to said line for controlling said signal, and a continuously rotating device to

In witness whereof, I hereunto subscribe my name this 11th day of December A. D., 1920.

RAY SETH WILBUR.
